UNITED STATES PATENT OFFICE.

OTTO M. REIF, OF PITTSBURGH, PENNSYLVANIA, ASSIGNOR TO HARBISON-WALKER
REFRACTORIES COMPANY, OF PITTSBURGH, PENNSYLVANIA, A CORPORATION OF
PENNSYLVANIA.

BRICKKILN.

Application filed July 12, 1924. Serial No. 725,601.

To all whom it may concern:

Be it known that I, Otto M. REIF, a citizen of the United States, and a resident of Pittsburgh, in the county of Allegheny and 5 State of Pennsylvania, have invented a new and useful Improvement in Brickkilns, of which the following is a specification.

This invention relates to down-draft brick kilns.

10 One object of the invention is to provide a kiln of a novel construction, for the purpose of producing more uniform heating of all of the bricks being burned. Another object is to so construct and divide the bottom 15 of the kiln that a maximum number of bricks being burned may be stacked in the kiln without obstructing outlet passages in the floor, while at the same time exposing all of the bricks substantially uniformly to the 20 heated gases of the kiln. Another object is to provide exhaust ports and draft passages connected therewith in the bottom of the kiln so arranged and constructed as to produce a substantially uniform down-draft 25 throughout the entire kiln, so avoiding the over-heating and under-heating of some bricks as compared to those in other portions of the kiln.

30 Other objects and advantages will be apparent to those familiar with the art from the following specifications:

Referring to the drawings, Fig. 1 is a central vertical section through a preferred form of the kiln on the line I—I of Fig. 2; 35 Fig. 2 is a horizontal section through the side walls of the kiln and a plan view of the bottom thereof, on the line II—II of Fig. 1; Fig. 3 is a horizontal section through the kiln on the line III—III of Fig. 1; Fig. 4 is a section on the line IV—IV of Fig. 1; Fig. 5 is a partial vertical section on the line V—V of Fig. 2; Fig. 6 is a partial vertical section on the line VI—VI of Fig. 2; Fig. 7 is a partial vertical section on the 40 line VII—VII of Fig. 2; Fig. 8 is a partial vertical section on the line VIII—VIII of Fig. 2; Fig. 9 is a partial vertical section on the line IX—IX of Fig. 8; Fig. 10 is a partial vertical section on the line X—X 45 of Fig. 2; Fig. 11 is a partial horizontal section and plan view of the bottom of a

modified kiln; Fig. 12 is a horizontal section at a lower level through the bottom of the kiln shown in Fig. 11; and Fig. 13 is a partial vertical section on the line XIII—XIII 55 of Fig. 11.

Referring to Fig. 1 the preferred form of this invention is embodied in a circular kiln having foundation walls 1, a circular side wall 2, lined with an inner firebrick 60 wall 2^a, and an arched dome 3. Built into the side walls of the kiln are a number of fire boxes 5, preferably equally spaced about the kiln wall. These have openings 6 leading to the exterior of the kiln. Doors 7 are 65 provided through the kiln walls 2 and 2^a to give access to the interior thereof. Stacks 8 are provided at intervals around the walls of the kiln, there being four illustrated, 70 equally spaced apart. These are preferably divided by an inner partition 9, into two vertical flues 10 and 11. These flues lead upward to outlets at or above the level of the top of the kiln, as in the standard kilns 75 of the form illustrated.

From the foot of each of the stacks 8 horizontal passages 12, 13, 14 and 15, respectively, lead to and terminate in central vertical wells 16, 17, 18 and 19, respectively. This arrangement is clearly illustrated in 80 Fig. 4. The passages are constructed in the brick work of which the whole bottom construction is built up.

As shown in Fig. 3, a section at a higher level, draft passages 20 and 21 extend outward from well 16 to the outer wall of the kiln. These are built into the brickwork of the bottom and at a higher level than the passage 12. Similar passages 22 and 23 extend outward from the well 18. From 90 the well 17, passages 24 and 25 extend outward to the outer wall of the kiln, and from the well 19 similar passages 26 and 27 extend.

The floor surface is divided by transverse narrow slot-like openings or ports 28 and 28^a extending downward into the floor body, and each of these ports crosses and is connected with one and only one of the draft passages 20, 21, 22, 23, 24, 25, 26 or 27, or else directly to one of the vertical wells 16, 17, 18 or 19. This arrangement is shown 95 100

by Figs. 1, 2, 3, 7, 8 and 10. The individual ports 28 and 28^a are separated at intervals by cross walls 29, so as to prevent any connection or short-circuiting between the several draft passages 20, 21, 22, 23, 24, 25, 26, 27.

At the outer ends of each of the said draft passages 20 to 27, inclusive, and at the side walls of the kiln, are curved terminal ports 10 or openings 30.

The ports 28, 28^a and 30 are so spaced from each other and arranged as to divide the floor of the kiln into rectangular blocks, so far as possible in a circular kiln. The 15 openings are so spaced apart as to permit stacks of standard sized bricks to be piled between them, allowing the usual space between the brick when arranged in checkered fashion for burning, so that the bricks will 20 not overlap or cover any of the openings 28, 28^a, or 30. As will be observed most of the floor of the kiln may be thus covered with rectangular stacks of bricks, arranged in separate piles, with very little waste space, 25 without any necessary covering of the openings through the flue surfaces, and leaving passages between stacks for circulation of the hot gases. Where the kiln is rectangular in shape, as it may be, the entire floor may 30 be divided into rectangular spaces by the outlet ports. The arrangement whereby the stacks of bricks do not lie over any outlet prevents breakage of the bricks immediately over the outlet, a result that frequently follows the present practice of overlapping the outlets.

The operation of this construction is as follows:

Heated gases are applied to the kiln from 40 the fire boxes 5 in the usual manner, the hot gases passing first toward the dome of the kiln. These gases then pass downward around and through the piles of brick and are drawn out through the slot-like openings or ports 28, 28^a and 30, the gases passing from these slotted openings to the draft passages 20—7, which in turn empty into the wells, 16, 17, 18 and 19, each of which is connected by lower draft passages 12, 13, 14 and 15 to one of the stacks 8. The draft from the stacks draws these gases off regularly, gently, and owing to the distribution of the outlet openings in the floor, the hot gases are drawn from the kiln over the 55 entire floor area thereof. Consequently, there is secured a uniform circulation of hot gas and distribution of heat throughout the kiln without any draft to a particular corner or side or portion of the kiln as in most down draft kiln constructions. The bricks are therefore burned with an unusual degree of uniformity and the fuel value of the gases of combustion is utilized with unusual efficiency.

65 The elongated ports in the floor act not

only as openings for the carrying off of the gases uniformly over the entire floor area, but they also form guides by which workmen placing the bricks in the kiln are enabled to so position and dimension their stacks of bricks as to utilize the floor space to the greatest possible advantage, and get into the kiln a maximum number of bricks for the area and space available.

In Figs. 11, 12 and 13 a modification is 75 illustrated in that instead of a plurality of stacks built into the wall of the kiln, a single stack 40 is provided at one side of and spaced away from the kiln. This stack is connected by two passages 41 and 42 to a central well 43 which in turn is connected by passages 44, 45, 46 and 47 to the rectangularly disposed ports or outlet openings 48 and 49 in the floor of the kiln. The outlets 48 and 49 are arranged in a different 80 order of rectangles in this modified form, and the stack connection is different, but otherwise the advantages and functions of the device are similar to those of the form of kiln above described in detail. 90

I claim:

1. In a down-draft brick kiln, a floor divided by narrow elongated outlet ports into substantially rectangular sections, said sections being adapted to receive and space apart rectangular stacks of bricks to be burned, and draft passages connecting said ports to an outlet stack. 95

2. In a down-draft brick kiln, a floor divided by narrow elongated outlet ports into spaces adapted to receive individual rectangular stacks of bricks to be burned, and means to draw hot gas from the kiln through the said ports simultaneously from all sections of the kiln floor. 100

3. In a down-draft brick kiln, a floor divided by a series of narrow elongated openings into a plurality of rectangular sections each adapted to receive and support a separate stack of bricks, and means to create a down-draft through each of the elongated floor openings between and around the stacks of bricks. 105

4. In a down-draft brick kiln, a floor divided by a plurality of separate narrow elongated outlet ports into a plurality of rectangular sections each adapted to support a stack of bricks to be burned, an exterior stack adapted to create a draft, a passage leading beneath the floor of the kiln from the exterior stack to a well at the middle portion of the kiln floor, and draft passages leading from the well to the said elongated outlet ports, whereby to draw off hot gases uniformly over the floor area from and around each of the rectangular sections of the kiln floor. 110

5. In a down-draft brick kiln, means to supply hot gas to the top of the kiln, a floor divided by narrow elongated openings 115 120 125 130

therein into a plurality of rectangular sections each of which is adapted to support a separate stack of bricks to be burned, draft passages in the floor connecting the said

whereby to draw the hot gas from the kiln between, around and through the stacks of bricks and uniformly from over the floor of 10 the kiln.

³ openings to central wells, and passages beneath said draft passages connecting said wells to stacks built in the wall of the kiln,

In testimony whereof, I sign my name.

OTTO M. REIF.
